UNITED STATES PATENT OFFICE.

STEPHEN SPOOR, OF PHELPS, NEW YORK.

IMPROVEMENT IN GATES.

Specification forming part of Letters Patent No. 59,930, dated November 20, 1866.

To all whom it may concern:

Be it known that I, STEPHEN SPOOR, of Phelps, in the county of Ontario and State of New York, have invented certain new and useful Improvements in Gates; and I do hereby declare that the following is a full and exact description thereof, reference being had to the accompanying drawings, making part of this specification.

Figure 1 is a side elevation of my improved gate in its natural closed position; Fig. 2, a similar view with its front end elevated for the passage of swine, &c.; Fig. 3, an elevation of the front end; Fig. 4, a view showing the friction-wheel and accompanying parts detached.

Like letters of reference indicate corresponding parts in all the figures.

My improvement belongs to that class in which the gate slides half-way back on a friction-wheel, and then swings around.

My invention consists in an improved arrangement of the gate, whereby one end may be elevated sufficiently for the passage of swine or other small animals, and in the employment of a swinging pendent catch in connection with the same for retaining the gate closed.

As represented in the drawings, A is the gate, and B C D the posts. The gate is made up of the ordinary slats and cleats a b. The post B has attached to it a cleat, E, by means of pins d f, &c., so as to leave space for the entrance of projections h i of the third and last rails, which are provided with notches k k, for catching over the pins d f, to hold the gate closed. The posts C D are set in the usual angular position, and have a friction-wheel, G, for the free sliding of the gate, whose construction will be presently explained.

Outside the post B, and at such a position as to strike over the projection h or i when resting upon the pin d, is hung a pendent catch, I, by means of a simple staple, m, being arranged so as to have a free play in every direction.

The great advantage of the arrangement as above described consists in the capability of the gate of being elevated at the front end, as shown in Fig. 2, to allow swine to pass, and in the simple pendent catch I, for holding over the projections h i, either in an elevated or depressed position.

To elevate, as in Fig. 2, it is simply necessary to open the gate a little distance to free the projections, and then raise the lower

one, i, to the position occupied by h on pin d. The projection striking the catch throws it out, and then, when the notch k strikes over the pin, the catch settles again over the top of the projection, and prevents displacement by the passage or the rooting of the swine.

Farmers have objected to gates of this class heretofore, for the reason that they have been deprived of the advantages of bars, that can be let down at any time to give free passage to hogs.

My arrangement of the gate secures this advantage in the simplest manner, for while the gate stops the passage of larger animals, hogs, sheep, &c., can easily pass under; and since the catch I always settles over the projections h i when in place, the gate cannot be displaced or opened by rooting or any ordinary action of the animals.

A pendent catch has before been employed, situated within a mortise of the post, and having weighted handles on the outside to operate it; but in such case it has simply a swinging motion in a longitudinal direction, and not a free universal motion.

It will be seen that my catch is on the outside, and no matter which way it swings, it will settle over and secure the gate in place. It is much cheaper and simpler than the device above referred to.

The wheel G is so arranged that the gate slides freely back and forth upon it, as usual.

In order to prevent freezing, and to obviate friction as much as possible, I form a turning-joint, consisting of a stationary bearing, n, having a flange, o, and a pin, p, that rests in the block H, and over this bearing fits a corresponding turning-socket, q, whose arms r r support the friction-wheel.

What I claim as my invention, and desire to secure by Letters Patent, is—

Adapting the gate to be elevated for the passage of swine, &c., by means of the two projections h i and pin d, and securing the same in place by means of the catch I, hanging free on the outside of the post, the whole arranged and operating substantially as and for the purposes specified.

In witness whereof I have hereunto signed my name in the presence of two subscribing witnesses.

STEPHEN SPOOR.
